United States Patent Office

Des. 191,196
Patented Aug. 29, 1961

191,196

HINGE OR SIMILAR ARTICLE

Vytant P. Aleks, Rockford, Ill., assignor to National Lock
Co., Rockford, Ill., a corporation of Delaware

Filed Feb. 27, 1961, Ser. No. 64,061

Term of patent 14 years

(Cl. D10—9)

FIG. 1 is a front elevational view of a hinge or similar article on a reduced scale embodying my new design;

FIG. 2 is a side elevational view taken from the left-hand edge of FIG. 1;

FIG. 3 is an end elevational view thereof.

I claim:

The ornamental design for a hinge or similar article, substantially as shown.
